UNITED STATES PATENT OFFICE.

RICHARD MURRAY, OF NEW YORK, N. Y.

BUILDING BLOCK.

Application filed April 25, 1922. Serial No. 556,491.

To all whom it may concern:

Be it known that I, RICHARD MURRAY, a citizen of the United States, and residing at New York, in the county of New York 5 and State of New York, have invented certain new and useful Improvements in Building Blocks, of which the following is a specification, such as will enable those skilled in the art to which it appertains to make 10 and use the same.

This invention relates to building blocks, and particularly to blocks of this class composed of concrete and used in the construction of the walls of buildings and 15 principally the outside walls of buildings, and the object of the invention is to provide a combination of blocks of this class by means of which the foundation of a building wall as well as the inner and outer 20 faces of such wall may be constructed by the use of my improved building blocks to produce the strongest possible wall and foundation construction at a minimum expense as well as to produce a wall construction 25 which will have the required features of constructions of this class; and with these and other objects in view the invention consists in building blocks of the class and for the purpose specified which are simple in 30 construction, efficient in use and which are constructed as hereinafter described and claimed.

The invention is fully disclosed in the following specification, of which the accompanying drawing forms a part, in 35 which the separate parts of my improvement are designated by suitable reference characters in each of the views, and in which:

40 Fig. 1 is a perspective view of a part of a building wall with part of the construction broken away and in section;

Fig. 2 a perspective detail view of one of my improved blocks;

45 Fig. 3 a perspective detail view of another of the blocks which I employ;

Fig. 4 a perspective detail view of another form of block which I employ; and,

50 Fig. 5 a partial section on the line 5-5 of Fig. 4.

In the practice of my invention and in the construction of a building wall, including the foundation thereof, I employ three distinct forms of building blocks 10, 11 and 55 12 shown in perspective detail in Figs. 2, 3 and 4 of the drawing. The block 10 is

oblong and rectangular in form and is of a thickness approximately one-half the depth of the block and in one face, preferably the bottom face 13 of the block, is 60 formed a number of compartments 14, and three of which are shown, and these compartments extend to within a predetermined distance of the top face of the block and open outwardly through the bottom 65 face thereof, and this block is preferably used as a foundation forming block and in Fig. 1 of the drawing, I have shown a number of the blocks 10 mounted one upon another and side by side with the compartments 14 directed downwardly as shown at the lower left hand corner of Fig. 1 of the drawing and, in practice, cement, concrete or the like is used between the adjacent faces of the block 10, and this concrete will extend upwardly a predetermined distance into the compartments 14 as shown at 15 in Fig. 1 of the drawing to anchor and retain the blocks 10 in predetermined 70 position.

The blocks 11 and 12 are adapted to be used in forming the wall construction of a building and are mounted upon the foundation blocks 10, as clearly shown in Fig. 1 of the drawing. The blocks 11 are oblong and rectangular in form and are provided with bores 16 extending longitudinally therethrough and opening outwardly through both ends of the block, and said blocks are adapted to be mounted upon the 80 foundation blocks 10 in the manner shown in Fig. 1 with the narrow side faces 17 of said blocks directed upwardly and downwardly and the wide faces 18 thereof directed inwardly and outwardly, and these 85 blocks are preferably mounted on the inner face of the building wall, the outer face of said wall being formed by the blocks 12.

The blocks 12 are of the same general form as the blocks 10 and 11 but are made hollow in form or provided with enclosed chambers 19, which are formed in the blocks by suitable core-pieces 20, which will form a permanent part of the blocks, and these core-pieces will be composed of inexpensive material and the blocks 12 will be mounted in the same manner as the mounting of the blocks 11 upon the foundation blocks 10 to form a neat and finished appearance on the outer face of the wall of a building, and by reason of the chambers 19 in the blocks 12 said blocks will be of considerably less 90 95 100 105 110

weight than if made solid, and will also be strong and durable and will form pockets or chambers which will aid in keeping the walls of a building in proper condition, and this is also true in the use of the blocks 11 which have the bores 16 extending therethrough.

It will also be apparent that in the construction of thicker walls and foundations, 10 the blocks 10, 11 and 12 may be used in other ways, and the blocks 11 and 12 may be mounted one upon another and side by side with the wide faces thereof directed upwardly and downwardly instead of the narrow faces thereof, as shown in Fig. 1 of the 15 drawing, and various changes in and modifications of the construction and method of using the building blocks herein shown and described may be made, within the scope of 20 the appended claims, without departing from the spirit of my invention or sacrificing its advantages.

Having fully described my invention, what I claim as new and desire to secure by 25 Letters Patent, is:—

1. A building wall and foundation construction of the class described comprising foundation blocks of predetermined form and having chambers opening through one 30 face thereof, said blocks being placed one upon another and side by side with the chambers thereof directed downwardly, and wall blocks mounted upon said foundation blocks, and the wall blocks at the inner side of 35 the wall having inter-communicating air spaces.

2. A building wall and foundation construction of the class described comprising foundation blocks of predetermined form

and having chambers opening through one 40 face thereof, said blocks being placed one upon another and side by side with the chambers thereof directed downwardly, and wall blocks mounted upon said foundation blocks, the wall blocks at the inner side of 45 the wall having inter-communicating air spaces, and the outer side being provided with dead air spaces.

3. A building wall and foundation construction of the class described comprising foundation and wall building blocks, 50 said foundation blocks being oblong and rectangular in form and provided in one face thereof with chambers, said foundation blocks being adapted to be placed one upon another and side by side with the chambers thereof directed downwardly, one of said wall blocks forming one 55 face of the wall construction being provided with dead air spaces.

4. A building wall and foundation construction of the class described comprising foundation and wall building blocks, said foundation blocks being oblong and rectangular in form and provided in one face 60 thereof with chambers, said foundation blocks being adapted to be placed one upon another and side by side with the chambers thereof directed downwardly, one of said wall blocks forming one face of the wall construction being provided with dead air spaces, and the other of said wall blocks being provided with inter-communicating bores.

In testimony that I claim the foregoing 75 as my invention I have signed my name this 22nd day of April, 1922.

RICHARD MURRAY.
